UNITED STATES PATENT OFFICE.

PETER KIMACK, OF ST. LOUIS, MISSOURI.

COMBINED RAIL ANTICREEPER, TIE PLATE, AND BRACE.

1,269,715.

Specification of Letters Patent. Patented June 18, 1918.

Application filed December 26, 1917. Serial No. 208,768.

To all whom it may concern:

Be it known that I, PETER KIMACK, a citizen of the United States, and resident of St. Louis, Missouri, have invented certain new and useful Improvements in Combined Rail Anticreepers, Tie Plates, and Braces, of which the following is a specification containing a full, clear, and exact description, reference being had to the accompanying drawings, forming a part thereof.

My invention relates to certain new and useful improvements in "combined rail anti-creeper, tie plate and brace" and has for its primary object the construction of a rail anti-creeper which engages with the edge of the rail base and the web of the rail, thus preventing the movement of the rail in either direction.

In the drawings,

20 Figure 1 is a perspective view of my invention applied for use.

Fig. 2 is a cross section taken on a line 2—2 of Fig. 3.

25 Fig. 3 is a section taken on a line 3—3 of Fig. 2, and

Fig. 4 is a bottom plan view of the tie plate.

Referring to the drawings, 5 indicates the tie plate which is provided with the usual 30 rail bearing surface, and on one end with hooked flanges 6, and a spike opening 7, and on the opposite end with a rail bearing shoulder 8 and spike openings 9.

Intermediate the spike openings 9 is a spike opening 10, and surrounding the same on the outside is a semi-circular flange 11, which forms a socket or bearing for the rail anti-creeper.

40 The rail anti-creeping device is illustrated in Figs. 1, 2 and 3 and consists of a body portion 12, provided with a strengthening rib 13 and with a serrated portion 14, which is adapted to engage the web 15 of the rail.

One end of the rail anti-creeper is provided with a semi-circular portion 16 through which is formed a round opening 18. The semi-circular portion 16 of the rail anti-creeper is adapted to snugly fit in the socket formed by the flange 11, and the opening 18 of the rail anti-creeper coincides with the spike opening 10, formed in the tie plate.

Formed in the rail anti-creeper is a serrated shoulder or biting surface 19, which is adapted to engage with the edge of the 55 rail base flange. The shoulder 19 when the

rail anti-creeper is in position, extends slightly below the base flange as illustrated in Fig. 2.

The tie plate 5 is secured to the tie by means of spikes 20, and the rail anti-creeper is secured to the rail by means of a spike 21. The spikes 20 and 21 are for the purpose of securing one rail base flange, and the opposite rail base flange is secured to the tie plate by means of the hooked flanges 6.

60 In installing my rail anti-creeper for use, the tie plate 5 is applied to the tie in the usual manner and by means of the spikes 20, and a spike passing through the opening 7. The rail is properly secured and then the 70 rail anti-creeper is applied to the tie plate and rail by placing the semi-circular portion 16 in the socket formed by the flange 11, and then by means of a spike 21 the rail anti-creeper is firmly secured in place, 75 the serrated portion 14 being held in contact with the web of the rail and the serrated portion 19 being held in contact with the edge of the base flange of the rail.

70 The serrated portion 14 is formed on an 80 arc of a circle, whose radius is greater than the distance from the face of the rail web to the vertical axis of the spike 21, on which the rail anti-creeper is arranged to rotate.

The serrated shoulder 19 which bites 85 against the edge of the base flange of the rail is formed on an arc of a circle, whose radius is greater than the distance from the vertical axis of the spike 21, to the outer face or edge of the rail base flange.

90 By the foregoing construction of biting or engaging surfaces 14 and 19, any longitudinal movement of the rail in either direction will cause both surfaces to firmly 95 clamp or bite into the rail and thus prevent its creeping in either direction, the serrated surface 14 acting against the web, and the serrated shoulder 19 acting against the edge of the base flange.

100 Extending from the body portion 12 of the rail anti-creeper is a projection 22 which is adapted to be inserted beneath the ball of the rail for preventing the rail anti-creeper from working away from the web. This projection 22 also acts as a rail brace.

105 In some instances the serrated portion 14 and the projection 22 may be omitted, in which event the rail creeping is prevented solely by the serrated portion 19 biting into 110 the rail base flange.

If it is desired to use the serrated portion 14 only, the vertical portion of the rail anti-creeper is eliminated.

The bottom of the tie plate is provided 5 with a series of intersecting ribs or flanges 23 which perform the usual function of flanges on the bottom of a tie plate.

Having fully described my invention, what I claim is:

10. 1. A rail anti-creeper comprising a tie plate provided on one end with hooked flanges for engaging one base flange of a rail, and on the other end with a rail bearing shoulder and spike openings intersecting 15 said shoulder, a socket arranged between said spike openings, and a locking dog provided with a serrated face pivotally mounted in said socket.

20. 2. A rail anti-creeper comprising a tie plate provided on one end with spaced hooked flanges and a spike opening and on the other end with a rail bearing shoulder and spike openings intersecting said shoulder and with a socket between the spike 25 openings, and a locking dog pivotally mounted in said socket said locking dog being provided with a serrated edge adapted to engage a rail base flange and with a portion projecting beyond the serrated edge and 30 overlying the top of the rail base flange.

35. 3. A rail anti-creeper comprising a tie plate provided with spike openings, hooked flanges on one end and a rail bearing shoulder on the other end and a socket between the spike openings, a locking dog provided with a cylindrical opening and a cam faced shoulder adapted to engage against the edge of the rail mounted in said socket, a rail bracing portion carried by said locking dog 40 adapted to be seated beneath the ball of the rail, and serrated surface carried by the locking dog and located between the rail brace and the cam face shoulder.

45. 4. A rail anti-creeper comprising a tie plate provided on its underneath surface with flanges, and on its top surface at one end with hooked flanges for engaging one

base flange of the rail, and at its opposite end, with a rail bearing shoulder and a socket, a pivoted locking dog mounted in 50 said socket, said locking dog being provided with a serrated cam faced shoulder adapted to bear against an edge of the base flange and provided with a portion extending beyond the shoulder adapted to lie on top of 55 the base flange, said locking dog being provided with a circular opening, and a spike seated in said opening for securing the locking dog to the rail.

5. A rail anti-creeper comprising a tie 60 plate provided on one end with hooked flanges spaced apart and a spike opening between said flanges and on the other end with a rail bearing shoulder and spike openings intersecting said shoulder and with a 65 socket between the spike openings the wall of the socket being a continuation of the rail bearing shoulder, and a locking dog pivotally mounted in said socket said locking dog being provided with a cam faced serrated shoulder adapted to engage the rail 70 base flange.

6. A rail anti-creeper comprising a tie plate provided on one end with hooked flanges spaced apart and with a spike opening between said flanges and on the other end with a rail bearing shoulder and spike 75 openings intersecting said shoulder and with a socket intermediate the spike openings the wall of which forms a continuation of 80 the rail bearing shoulder, a dog provided with a serrated cam faced shoulder pivotally mounted in said socket for engaging the base flange of a rail, and a series of ribs formed on the underneath surface of said 85 plate.

In testimony whereof, I have signed my name to this specification, in presence of two subscribing witnesses.

PETER KIMACK.

Witnesses:

SUE PFEIFFER,
EDWARD E. LONGAN.
